UNITED STATES PATENT OFFICE

2,352,260

WHISTLING PROJECTILE

Victor George Herman, New York, N. Y.

Application October 15, 1941, Serial No. 415,014

7 Claims. (Cl. 102—92.5)

My present invention relates to projectiles and has for its main object a construction by which projectiles are producing a screaming and whistling sound during flight.

It must be stressed that this screaming sound can be heard over the entire distance being covered by the projectile during flight. Moreover, the screaming noise caused by the projectile creates the impression of a much greater number of shells as there actually are. Thus the noise caused by this new type of projectile proposed herewith is not only greater, but also extends over a much larger area than in case of projectiles of the usual type.

It is a further object of my present invention to combine this effect with means to eliminate as far as possible the vacuum caused by the rear face of the projectile during flight.

It is another object of my present invention to provide also means to close any air passages provided in the projectile and in the opening at the rear face of the same until the projectile has left the bore of the gun.

With the above objects in view, my present invention chiefly consists in combining with a projectile a whistling device built into the same in such a manner as to produce a whistling sound during the flight of this projectile.

In accordance with a preferred embodiment of my invention I provide in a projectile in combination at least one air passage communicating at both ends with the exterior and a whistling device built into this air passage and functioning in the above described away.

This air passage may extend either only in the nose pieces or from the nose to the cylindrical side wall of the projectile or from this side wall to the rear projectile face. In latter case this air passage is not only adapted to contain the whistling sound producing device but serves also for reducing or eliminating as far as practicable the vacuum set up by the rear face of the projectile.

In another embodiment of my present invention I combine in a projectile two bores: one of these bores communicates at one end through the shoulder of the nose or the cylindrical wall of the projectile with the exterior and is closed at its other end; and the other bore is connected at one end with the above bore and communicates at its other end with the exterior. These two bores are shaped in such a manner as to be adapted to act together as whistle and to produce a whistling sound during the flight of the projectile.

The novel features which I consider as char-

acteristic for my invention are set forth in particular in the appended claims. The invention itself, however, both as to its construction and its method of operation, together with additional objects and advantages thereof, will be best understood from the following description of specific embodiments when read in connection with the accompanying drawing, in which:

Figure 1 is a side view of a projectile constructed in accordance with my present invention, partly in section;

Figure 2 is a side view of a modification of the projectile shown in Fig. 1, partly in section;

Figure 3 is an end view of the projectile shown in Fig. 2;

Figure 4 is a longitudinal section of still another embodiment of my present invention;

Figure 5 is a longitudinal section of a part of a projectile provided with two cooperating bores as whistling device;

Figures 6 and 7 are longitudinal sections of two modifications of the projectile shown in Fig. 5; and

Figure 8 is a side view of a projectile equipped with a series of whistle-like cooperating bores provided with a common closing plate for the openings of these bores in the rear face of the projectile.

Referring now to the drawing in which like characters of reference designate similar parts in the various views, 10 designates the projectile bearing on its rear part a rotating or driving flange 11. Projectile 10 consists, as usual, of casing 12 containing the explosive material 13 and a nose 14 in which a fuse is arranged.

In accordance with my present invention air passages are provided in casing 12 and/or nose 14 of the projectile.

In the projectile shown in Fig. 1 each of the air passages 15 is communicating with the exterior at one end through an opening 16 in the nose 14 and at its other end through an opening 17 in the side wall of casing 12. A whistling member 18 of any conventional type is arranged in this air passage in such a manner as to produce a whistling sound during flight of projectile 10.

It is important that air passage 15 and all other air passages described below in detail be arranged in such a manner as to enable entering of air through its front opening during rotation of the projectile. Therefore it is advantageous to arrange these air passages inclined to the axis of rotation of the projectile; if possible

these air passages should be of helical shape arranged coaxially with the axis of rotation.

In Fig. 2 another embodiment of my invention is shown. Each of the air passages 19 communicates with the exterior at the one end through an opening 20 in the side wall of casing 12 and at its other end through an opening 21 in the rear face 22 of the projectile. Also in this case a whistling member is arranged in each of the air passages 19.

It is well known that during flight of the projectile a vacuum is set up behind the rear face 22. The air flowing through passages 19 eliminates, as far as practicable, this vacuum.

As shown in Fig. 3 I prefer to arrange a number of air passages 19 and arrange their openings 21 substantially evenly distributed over the rear face 22 of the projectile. This results in substantially complete elimination of the vacuum behind the rear face.

As shown in Fig. 4, it is also possible to provide tubes 23 serving as air passages. Each of these tubes communicates with the exterior at its front end through an opening 24 in the projectile nose 14 and at its rear end through opening 25 in rear face 22. Also in each of these tubes a whistling device 18 is arranged in the above described way.

The whistling devices 18 may be secured in their required position in the tube either by shoulder 45, shown in Figs. 2 and 4, or by conical shaping of the bores 15, as shown in Fig. 1.

It is important that during ignition of the powder charge used for firing the projectile the openings 25 be closed, so that the full pressure of the expanding gases may act when expanding on the rear face 22 of projectile 10. In order to attain this object, I provide means adapted to close openings 25 during firing; these means must be arranged in such a manner, however, as to get detached from the projectile after the same has been leaving the bore of the gun. I have found that a plate 26 may very well serve this purpose; this plate may be held in contact with the rear face 22 either by adhesion caused by highly polished contacting faces or by some adhesive provided between these contacting pieces or by making this plate magnetic. In the latter case, the plate is held during firing of the projectile by magnetic force in contact with the rear face 22; after the projectile is leaving the bore of the gun, the pressure of air entering the air passages through their front openings causes this magnetic plate 26 to become detached from rear face 22, enabling thereby passage of air through these passages.

It should be stressed that the expression "whistling device" or "whistling means" as used in the present specification and appended claims is intended to be understood in its broadest sense; this means that all devices which are adapted to cause a whistling sound when exposed to an air flow should be comprehended within the meaning of the above expression. Thus, for instance, this whistling device may consist of one or more vibrating members arranged stationary or rotatably within the air passage.

In Figures 5-8 of the drawing I have shown whistling devices composed of two bores: The first bore communicates at its front end with the exterior and is closed at its rear end; the second bore is connected at its one end with the first bore and communicates at its other end with the exterior. The relative position and arrangement of these bores must be such that the air

flow entering through the front opening of the first bore causes a whistling sound during flight of the projectile.

In the embodiment shown in Fig. 5 both bores 5 are arranged in nose 14 of the projectile: Bore 27 communicates through its front opening 28 with the exterior and is closed at its rear end 29. Bore 30 communicates at its one end through opening 31 with bore 27 and at its other end 10 through opening 32 with the exterior. Both bores 27 and 30 are arranged in such a manner as to form between them a projecting whistling edge 33. This whistling edge is producing in combination with bore 27 a whistling sound during flight of the projectile. In some cases it is advantageous to make opening 32 larger than the connecting opening 31 in order to avoid damping of the sound oscillations caused by vibration of the air column in bore 27.

In Fig. 6 another embodiment of my invention is shown: Bore 34 communicates at its front end through the opening 35 in the nose 14 with the exterior, and is closed at its rear end 36. As shown, the main portion of this bore is arranged in the side wall of casing 12. Bore 37 connects bore 34 with the exterior in the above described way. The sole difference is that opening 38 is provided in the side wall of casing 12 behind flange 11. The air escaping through opening 38 eliminates or at least substantially reduces the vacuum set up by this flange. The relative arrangement of bores 34 and 37 is also such as to cause a whistling sound during flight of the projectile.

As shown in Fig. 7 it is also possible to provide the front opening 39 of the first bore 40 in the cylindrical side wall of casing 12 and to arrange opening 41 of the second bore 42, which communicates with the exterior, in the rear face 22 of the projectile. In this case it is advisable to provide a cover plate 43 of the above described type. As shown in this figure this cover plate may be arranged sunken into the rear face of the projectile avoiding thereby that this plate be removed earlier than required.

The arrangement shown in Fig. 8 is very similar to the one shown in Fig. 7. The main difference is that one common closing cover 44 is provided for closing openings 41 of a series of whistling bores. This cover 44 is made of magnetic material and fits into a corresponding recess 45 in the rear face 22 of the projectile.

It will be understood that each of the elements described above, or two or more together, 55 may also find a useful application in other types of projectiles differing from the types described above.

While I have illustrated and described the invention as embodied in projectiles, I do not intend to be limited to the details shown, since various modifications and structural changes may be made without departing in any way from the spirit of my invention.

Thus, for instance, the term "projectile" as used throughout the above specification and the following claims is intended to comprehend not only shells or the like fired from projectile propelling apparatus, as cannons, guns or the like, but also bombs dropped from air planes.

Without further analysis, the foregoing will so fully reveal the gist of my invention that others can by applying current knowledge readily adapt it for various applications without omitting features that, from the standpoint of prior art, fairly constitute essential characteristics of

the generic or specific aspects of this invention and, therefore, such adaptations should and are intended to be comprehended within the meaning and range of equivalency of the following claims.

What I claim as new and desire to secure by Letters Patent is:

1. In a projectile having a body of generally cylindrical contour, at least one air passage within said body being open at both ends and communicating at said ends with the exterior, and means producing a whistling sound arranged within said projectile body and combined with said air passage within said body in such a manner as to produce a whistling sound during the flight of said projectile.

2. In a projectile having a body of generally cylindrical contour, an air passage within said body extending at least partly in longitudinal direction of said projectile, said air passage being open at both ends and communicating at said ends with the exterior, and means producing a whistling sound arranged in said air passage within said body in such a manner as to produce a whistling sound during the flight of said projectile.

3. In a projectile having a body of generally cylindrical contour, in combination at least one air passage within said body extending in longitudinal direction thereof and opening at one end through the nose and at the other end through the rear face of said projectile and whistling means arranged within said projectile body and combined with said air passage within said body in such a manner as to produce a whistling sound during the flight of said projectile.

4. In a projectile having a body of generally cylindrical contour in combination an air passage within said body extending in longitudinal direction thereof, said air passage being open at both ends, opening at one end through the cylindrical side wall and at the other end through the rear face of said projectile, communicating at both said open ends with the exterior, and whistling means arranged within said projectile body and combined with said air passage within

said body in such a manner as to produce a whistling sound during the flight of said projectile.

5. In a projectile having a body of generally cylindrical contour, an air passage within said body extending in longitudinal direction thereof, said air passage being open at both ends and communicating with the exterior at its one end through the front end of said projectile body and at its other end through the shoulder of the nose of said projectile body, and whistling means built into said air passage in such a manner as to produce a whistling sound during the flight of said projectile.

6. In a projectile having a body of generally cylindrical contour, at least one air passage within said body extending in longitudinal direction thereof, said air passage being open at both ends and communicating with the exterior at one end through the nose and at the other end through the rear face of said projectile body, whistling means built into said air passage in such a manner as to produce a whistling sound during the flight of said projectile, and a cover plate arranged on said rear face of said projectile body in such a manner as to cover the opening of said air passage in said rear face during firing of said projectile and to be detached therefrom during its flight.

7. In a projectile having a projectile body of generally cylindrical contour, at least one air passage within said body extending in longitudinal direction thereof, said air passage being open at both ends and opening at one end through the nose and at the other end through the rear face of said projectile body, whistling means built into said air passage in such a manner as to produce a whistling sound during the flight of said projectile, and a cover plate of magnetic sheet metal adapted to cover the opening of said air passage within said projectile body in said rear face of said body during firing of said projectile and adapted to be detached therefrom during flight of said projectile.

VICTOR GEORGE HERMAN.
